MRS. CAROLINE M. LORING AND EZEKIEL AVERELL, OF CHARLESTOWN,
MASSACHUSETTS.

Letters Patent No. 71,397, dated November 26, 1867.

IMPROVED NURSERY-CHAIR.

The Schedule referred to in these Letters Patent and making part of the same.

TO ALL WHOM IT MAY CONCERN:

Be it known that we, C. M. LORING and EZEKIEL AVERELL, both of Charlestown, in the county of Middlesex, in the State of Massachusetts, have invented a new and useful Improvement in Nursery-Chairs; and we do hereby declare that the following is a full, clear, and exact description of the same, reference being had to the drawing accompanying this specification, and making part of the same, in which—

Figure 1 is a perspective view of the combined chair and standing-stool.

Figure 2 is a separate view of the chair; and

Figure 3 is a view of the plaything-holder or table.

Similar letters of reference indicate like parts in all the figures.

The object of this invention is to combine in one article of furniture a child's chair, a dining-chair, and a standing-stool, in such a manner that each, when separate, may be used for the purpose designed, and when combined will make a dining-chair for children.

a, fig. 1, represents the standing-stool, which may be used separately from the chair *b*, for the purpose of assisting a child in learning to walk, and retaining it on its feet. On the top of this stool is placed the chair *b*, the legs of this chair fitting into holes on the top of the stool *a*, where it is held firmly. This chair is made to serve the purpose of an ordinary child's chair, having a hinged seat, *c*, fitting in place, as in fig. 1, when not in use as a privy-chair, for which purpose it may also be used. The plaything-holder or table *d* may be attached to the chair *b* or to the standing-stool *a*, having on each side pins *e e*, which fit into corresponding recesses in the arms of the chair *b*, the arms being made sufficiently elastic to spring out to admit the pins coming back into place, and holding the table when fitted in. On each side of the standing-stool are placed two arms *ff*, on which the table *d* is placed when required. These arms are pivoted at the end, under the stool, so as to be moved in under the stool when not in use.

The chair and stool should be made of such materials as will best answer the purpose, and the height, when combined, should be convenient for use at a dining-table by a child. The combination of the chair and stool in the manner shown makes a very useful article of furniture, easily put together, and not occupying much space. It may be used for a variety of purposes, and when combined as a dining-chair is safe, and not liable to be upset.

Having fully described our invention, what we claim as new, and desire to secure by Letters Patent, is—

The combination of the stool *a* and chair *b*, having the several parts arranged substantially in the manner as described and shown.

MRS. CAROLINE M. LORING,
EZEKIEL AVERELL.
